UNITED STATES PATENT OFFICE.

CHARLES L. BUTTERFIELD AND JONAS SAWDON, OF GRAND LEDGE, MICHIGAN, AS
SIGNORS OF ONE-THIRD TO GLEN L. KARR, OF DETROIT, MICHIGAN.

PRIMER.

Application filed December 19, 1923. Serial No. 631,478.

Our invention aims to provide a priming device for internal combustion engines ordinarily supplied with atomized or vaporized fuel from the carburetor connected to the engine by an intake manifold communicating with the cylinders of the engine, gasoline, kerosene or other fuel as ordinarily used and our invention aims to use quantities of such fuel for priming purposes, the fuel being atomized within the intake manifold of the engine so that it may be drawn into the cylinders of the engine for priming and starting purposes.

For atomizing the fuel in the intake manifold of the engine, for priming purposes, we use a small electric motor attached to the intake manifold for driving a distributor head within the manifold, and provision is made for delivering fuel to said distributor head, in various ways, so that the fuel may be atomized by centrifugal force set up by the driven distributor head.

Our invention also includes novel means for simultaneously controlling the starting of the electric motor and the admission of priming fuel to the distributing head within the intake manifold of the engine, and we have made provision for supplying air to the distributing head so that it may communicate with the atomized priming fuel and afford a desired admixture of air and gas for priming purposes.

Our invention will be hereinafter specifically described and then claimed, and reference will now be had to the drawings, wherein

Figure 1 is a side elevation of a portion of an internal combustion engine provided with a priming device in accordance with our invention;

Fig. 2 is an enlarged longitudinal vertical sectional view of part of the priming device;

Fig. 3 is a longitudinal sectional view of one form of fuel distributing and atomizing head;

Fig. 4 is a side elevation of another form of distributing and atomizing head;

Fig. 5 is a cross sectional view of the same;

Fig. 6 is a longitudinal sectional view of another form of distributing and atomizing head;

Fig. 7 is a cross sectional view of the priming device;

Fig. 8 is a horizontal sectional view taken on the line VIII—VIII of Fig. 7;

Fig. 9 is a plan of a portion of the priming device;

Fig. 10 is an enlarged cross sectional view of the distributing head taken on the line X—X of Fig. 2;

Fig. 11 is an enlarged longitudinal sectional view of a control device, and

Fig. 12 is a cross sectional view of the same.

In the drawings, the reference numeral 1 denotes a portion of an internal combustion engine having a carburetor 2 connected to the engine 1 by an intake manifold 3 which establishes communication between the carburetor and the cylinders of the engine 1 for the main supply of an explosive mixture to the engine cylinders.

In order that our priming device may be conveniently installed and used in connection with the engine 1, we provide the manifold 3 with an opening 4 having its walls screwthreaded to receive the exteriorly screwthreaded reduced portion 5 of a motor end member 6 and said end member may be locked in engagement with the side wall of the manifold 3 by a jam nut 7 or other device. The motor end member 6 supports a conventional form of small electric motor 8 including a field 9, armature 10, and commutator 11, brush holders 12 and 13, and an armature shaft 14. The armature shaft 14 extends into the enlarged inner end of a bore 15 axially of the motor end member 6 and said armature shaft has a reduced outer end or shank 16 extending through a reduced portion 17 of the bore 15, which reduced portion is axially of a nozzle 18 on the inner end of the reduced portion 5 of a motor end member 6. The nozzle 18 is preferably integral with the motor end member 6 and extends in proximity to the axis of the manifold 3.

The motor end member 6 is provided with a vent 19 communicating with the bore 15 and the armature shaft 14 is slightly reduced as at 20, to provide an annular chamber in communication with the vent 19 and a lubricant passage 21 formed in the lower part of the motor end member 6. Mounted in the outer end of the lubricant passage 21 is a conventional form of lubricant holding cup

or receptacle 22 adapted to hold a lubricant 23 and the lower end of a wick 24 which extends through the passage 21 to the bore 15 to supply, by capillary attraction lubricant 5 to the armature shaft without flooding the same, the lubricant being prevented from entering the reduced portion 20 of the bore 15 by the annular shoulder 25 of the armature shaft 14. The lubricant cup 22 may be 10 removed when it is to be filled or it may be supplied with lubricant through a bore 26 in the motor end member 6 communicating with the lubricant passage 21 intermediate its ends. See Fig. 7.

15 The motor end member 6, at one side of the bore 15, is provided with an opening 27 and mounted in one end of said opening is an adjustable tubular valve seat member 28 that may be adjusted and mounted in the 20 motor end member 6 by a nipple 29 attached to the motor end member 6 and to a fuel supply conduit 30 leading from the fuel supply connection 31 of the carburetor 2, as best shown in Fig. 1.

25 Adjustable in the opposite end of the opening 27 is a screw needle valve 32 provided with a crank-arm 33 and encircling said valve and attached to said crank and the member 6 is a coiled spring 34 which holds 30 the valve normally closed and seated on the valve seat member 28, but permits of the crank 33 being actuated to partially rotate the screw valve and unseat it.

35 Communicating with the opening 27, adjacent the valve seat member 28, is a port 35 extending at an angle to the axis of the bore 15 and opening at the nozzle 18 to discharge gasoline or other fuel at the end of said nozzle.

40 Adjacent the fuel control needle valve 32 is an air control valve 36, similar to the valve 32, and adjustable to and from an angularly disposed port 37 communicating with the reduced end 17 of the bore 15, the 45 port 37 receiving air from an atmospheric port 38 when the valve 36 is open.

45 Mounted on the outer end or shank 16 of the armature shaft 14 is a hollow head 39 designed for distributing and atomizing gasoline or similar fuel, said head being in the 50 form of a horizontally disposed cup which has its closed end fixed on the armature shaft 14 and its open end surrounding the nozzle 18. The head is adapted to receive 55 liquid fuel from the port 35 and air from the end 17 of the bore 15, although the use of air is optional. In the hollow head 39 are a multiplicity of discharge openings 40 adjacent vanes 41 on the periphery of the head, 60 the openings and vents being preferably radially disposed in circumferential rows, as best shown in Figs. 2 and 10. With the head 39 fixed on the armature shaft, the motor in operation, and the valve 32 open, fuel 65 will be supplied to the head 39 to be atom-

ized and discharged by said head. As the head is rapidly revolved centrifugal force causes the fuel to be thrown from the head and placed in a finely divided state which may be made more gaseous by the admission 70 of air.

Instead of using the form of head just described we may make the head of a series of nested sheet metal cups 42, as shown in Fig. 3, or mount spaced bladed disks 43 on 75 the armature shaft, as shown in Figs. 4 and 5, the disks being in proximity to each other and providing clearance for a fuel supply pipe 44 adapted to deposit fuel between the disks where it may be broken up and thoroughly atomized by the action of the driven bladed disks. Then again, we may use a hollow head 45 by mounting its inner end on the armature shaft 16 and let the fuel supply pipe 46 extend into the outer end of the head. 80 In this instance the fuel supply pipe 46 is carried by that wall of the manifold 3 opposite the motor end member 6, and as shown in Fig. 4 the fuel supply pipe 44 is independent of the motor end member 6. It is now 85 apparent that we have disclosed three ways of supplying fuel to the distributing and atomizing head which in itself may be designed to atomize the fuel used for priming purposes. 90

95 For controlling the operation of the electric motor and the valves 32 and 36, we employ a control device that may be advantageously located on the instrument board 47 of an automobile or any support contiguous to the engine 1. The control device includes a bracket 48 suitably mounted in the instrument board 47, said bracket having opposed portions 49 for insulated spring pressed contact members 50 and 51. The contact member 51 is connected by a wire 52 to the brush 13 of the motor and the other brush 12 of said motor is connected by a wire 53 to a suitable source of electrical energy (not shown). The same source of electrical energy is adapted to be connected by a wire 54 to the brush 50. The spring pressed contacts 50 and 51 normally engage a tubular insulator 55 slideable in the bracket 48, said insulator having its inner end provided with a sleeve contact member 56 which may be engaged by the contact members 50 and 51 to complete an electrical circuit for the motor 8. In the insulator 55 is a handle rod 57 provided with a handle or button 58 and connected to said handle rod and the crank 33 is a reach rod 59 to which may be connected a branch rod 60 for the crank of the air valve 36. This branch rod 60 may be disconnected from the main reach rod 59 when air is not to be used 115 in connection with the priming gas. The control device just described serves as a switch for controlling the operation of the motor 8 and when the switch is closed by a pull upon the handle or knob 58 the fuel 120 130

valve 32 is opened so that suction in the manifold 3 will raise fuel into the distributing and atomizing head to be discharged and atomized by centrifugal force produced by the motor driven head.

By supplying fuel to the distributing and atomizing head independent of the armature shaft 14, we can use the ordinary electric motor by simply substituting our motor end member for one of the usual end heads of an electric motor. We need only provide an armature shaft extension and by using a conventional form of motor we materially reduce the cost of manufacture in connection with our device. While the device has been primarily designed for the explosive engines of automobiles and similar vehicles, yet it will be understood that the priming device may be used in connection with any engine requiring a priming fluid for starting purposes.

What we claim is:—

1. The combination of an engine intake manifold, a motor end member connected to the manifold and extending therein, an electric motor connected to said end member and having an armature shaft extending through said end member into said manifold, a distributing and atomizing head in said manifold on the armature shaft of said motor and adapted to be revolved by said motor to dis-

tribute and atomize fuel by centrifugal force, said motor end member being ported for the admission of fuel and air to said head, valves controlling the supply of fuel and air to the ported end member, and means adapted to simultaneously control said valve and the operation of said motor.

2. The combination called for in claim 1, wherein the last mentioned means includes a handle rod connected to said valve and a switch associated with said handle rod.

3. The combination of an engine intake manifold, a motor end member extending into said manifold, a motor carried by said member and having a driven shaft extending into said manifold, a distributing and atomizing head in said manifold and enclosing that end of said motor end member in said manifold, fuel supply means for said head introducing fuel between said motor shaft and motor end member into said head, a valve controlling said fuel supply means, a handle rod connected to said valve, and a switch associated with said handle rod and adapted to control the operation of said motor driven head.

In testimony whereof we affix our signatures.

CHARLES L. BUTTERFIELD.
JONAS SAWDON.
